UNITED STATES PATENT OFFICE.

MINER BARCUS, OF SCHENECTADY, NEW YORK, ASSIGNOR TO GENERAL ELECTRIC COMPANY, A CORPORATION OF NEW YORK.

WINDINGS FOR ELECTRICAL APPARATUS.

No. 856,566.

Specification of Letters Patent.

Patented June 11, 1907.

Application filed October 31, 1906. Serial No. 341,403.

To all whom it may concern:

Be it known that I, MINER BARCUS, a citizen of the United States, residing at Schenectady, county of Schenectady, State of New York, have invented certain new and useful Improvements in Windings for Electrical Apparatus, of which the following is a specification.

My invention relates to windings for electrical apparatus, such as reactance coils and transformers, and has particular reference to a type of winding that has been proposed heretofore for high-current capacities comprising a plurality of sections each composed of a plurality of insulated strands wound one outside the other, the several sections being connected in series. By stranding the conductor, eddy-currents are avoided. Forming the conductor out of insulated strands wound one outside the other is a convenient method of stranding, and by giving the conductor a twist near its center the outside strands of a portion of the sections may be connected in series with the inside strands of the remaining sections, so that differences in induced voltages due to the different areas of the turns formed by the inside and outside strands are compensated for and short-circuit currents are avoided.

The object of my invention is to increase the adaptability of windings of this type. The space in the core in which the winding must be placed is often fixed both in size and shape since it is ordinarily desirable to employ the same core punchings and castings for windings of different voltages. If a core has been designed for a winding of a given number of turns, and it is desired to use the same core for a winding having, say 50 per cent. more turns and correspondingly reduced cross-section, two obvious arrangements may be employed. In the first place, the width of the strands may be decreased so as to make room for a greater number of sections side by side; or second, the depth of each section may be decreased so as to make room for two layers of sections. The first of these methods may be undesirable mechanically, since if the width of the strands is reduced below a certain amount with respect to the depth of the section, the section becomes mechanically weak. Employing two layers, on the other hand, is disadvantageous, since the effective radiating surface is de-

creased so that a greater amount of copper is required.

My invention consists in a novel arrangement of the winding, whereby I am enabled to avoid the disadvantage of both the methods mentioned above.

My invention consists in connecting the greater portion of the strands of each section so as to form a stranded conductor common to all the sections and connecting the remaining strands, so as to form a plurality of conductors, each common to a portion only of the sections and connecting these last-mentioned conductors in parallel with each other and in series with the first-mentioned conductor. For instance, if after a given winding has been designed, it is desired to adapt it for 50 per cent. higher voltage, the strands forming the inner two-thirds of each section may be connected together so as to form a conductor with a number of turns corresponding to the number of sections. Then the remaining strands of one-half the sections may be connected together to form a conductor of one-half the cross-section and one-half the number of turns of the first conductor and the remaining strands of the remaining sections may be connected to form a similar conductor. These last two conductors may be connected in parallel with each other, so as to give a cross-section equal to $\frac{1}{3}$ that of the first conductor, and may then be connected in series with the first conductor. In this way, the winding is divided so as to form a conductor of 50 per cent. more turns and two-thirds the cross-section of the original winding.

My invention will best be understood by reference to the accompanying drawings, in which

Figure 1 shows a side elevation, partly in cross-section, of a transformer or reactance-coil arranged in accordance with my invention; Fig. 2 shows an enlarged plan view of the winding and end connections; and Fig. 3 shows a perspective view of the same.

In the drawing, A represents the enclosing casing, and B the laminated core carried within the casing. This core is shown as of the well-known shell type.

C represents the winding passing through openings in the core and comprising a plurality of sections c' to c", as shown in Figs. 2 and 3. Each of these sections is composed of

plurality of insulated strands arranged, one outside the other, as is most clearly shown in Fig. 3. The strands forming the inner two-thirds of each section are connected to form a 5 stranded conductor common to all the sections. One terminal of this conductor is shown entering section c^1 at 1 in Figs. 2 and 3. This conductor extends through all the sections in series, including the strands forming 10 the inner two-thirds of each section, and has its other end at section c^6 at the point 2. This conductor may be given a twist at its middle point between sections c^3 and c^4 , as indicated at 3, so that the outer strand of this conductor 15 on one side of the twist becomes the inner strand on the other side of the twist, and the voltages induced in all the strands of the conductor are equalized. On leaving the section c^6 at the point 2, this conductor divides 20 into two equal parts,—one part passing through the outer strands in series with the sections c^1 , c^2 and c^3 , and the other part passing through the outer strands in series of the sections c^4 , c^5 and c^6 . Thus two other stranded 25 conductors are formed,—one entering section c^1 at 4, and leaving section c^3 at 5, while the other enters section c^4 at 6, and leaves section c^6 at 7. The ends 5 and 7 are connected 30 together, as clearly shown in Fig. 3. These 35 two conductors, each of which is of half the cross-section of the conductor first described, are connected in parallel with each other, and in series with the first conductor. In this manner the six sections are connected to form a stranded conductor with nine effective turns and with a cross-section equal to two-thirds the cross-section of each section.

Other combinations of connections may be employed to secure other ratios of the number of turns and of cross-section, in accordance with the principles above explained. Accordingly, I do not desire to limit myself to the particular construction and arrangement of parts here shown, but aim in the appended 45 claims to cover all modifications which are within the scope of my invention.

What I claim as new and desire to secure by Letters Patent of the United States, is,—

1. A winding for electrical apparatus comprising a plurality of sections each composed of a plurality of insulated strands arranged one outside the other, a portion of the strands of each section being connected to form a stranded conductor common to all of said 50 sections and the remaining strands being con-

nected to form a plurality of conductors each common to a portion only of said sections.

2. A winding for electrical apparatus comprising a plurality of sections each composed of a plurality of insulated strands arranged one outside the other, a portion of the strands of each section being connected to form a stranded conductor common to all of said sections and the remaining strands being connected to form a plurality of conductors 60 each common to a portion only of said sections, said last mentioned conductors being connected in parallel with each other and in series with the first mentioned conductor.

3. A winding for electrical apparatus comprising a plurality of sections each composed of a plurality of insulated strands of equal cross-section arranged one outside the other, the greater portion of the strands of each section being connected to form a stranded conductor common to all of said sections and the remaining strands being connected to form a plurality of conductors each common to a portion only of said sections, said last mentioned conductors being connected in parallel with each other and in series with the first mentioned conductor.

4. A winding for electrical apparatus comprising a plurality of sections each composed of a plurality of insulated strands arranged one outside the other, the inner strands of each section being connected to form a stranded conductor common to all of said sections and the outer strands being connected to form a plurality of conductors each 75 common to a portion only of said sections.

5. A winding for electrical apparatus comprising a plurality of sections each composed of a plurality of insulated strands arranged one outside the other, the inner strands of each section being connected to form a stranded conductor common to all of said sections and the outer strands being connected to form a plurality of conductors each 80 common to a portion only of said sections.

6. A winding for electrical apparatus comprising a plurality of sections each composed of a plurality of insulated strands arranged one outside the other, the inner strands of

each section being connected to form a stranded conductor common to all of said sections,

and the outer strands being connected to form a plurality of conductors each common to a portion only of said sections,

the first mentioned conductor being twisted intermediate its ends so that the outside

strand on one side of the twist is the inside

strand on the other side of the twist.

In witness whereof, I have hereunto set

my hand this 30th day of October, 1906.

MINER BARCUS.
